ADJUSTABLE AWNINGS

Vladimir Jedlicka and James J. Jedlicka, Chicago, Ill.

Application June 19, 1953, Serial No. 362,880

5 Claims. (Cl. 20—57.5)

Our invention is directed to novel multiple and adjustable awnings which include an auxiliary pivoted awning adapted to be selectively mounted in the desired depending position substantially below the outer edge portion of the main inclined awning.

It is an important object of our invention to provide a multiple awning having a main normally inclined awning frame and panels or louvers thereon and having track means mounted along and below said main awning and having an auxiliary adjustable sun shield or awning adjustably suspended below the outer edge portion of the main awning and having slidable mechanisms whereby said auxiliary dependable awning may be retracted and elevated to normally inoperative positions adjacent to and below the main awning.

A further object of our invention is the provision of novel mechanism for operating a movable auxiliary awning with respect to a main awning and which provides for retracting movement and elevation of such auxiliary awning into an upper and normally concealed position adjacent the underside of the main awning.

A further object of our invention is the provision of awning structures having an auxiliary awning and means for pivotally connecting such auxiliary awnings to slideable means operatively connected to the main awning by means of a pair of tracks, rods or the like whereby selective projection and retraction of said auxiliary awning may be quickly and easily effected. Other and further objects of our invention will be apparent from the following description and appended claims.

On the drawings:

Fig. 1 is a perspective view of one of our novel awnings illustrating the auxiliary awning thereof in depending suspended position and bracing means therefor.

Fig. 2 is a cross sectional view taken substantially on lines 2—2 of Fig. 2, and illustrating the mounting of a slideable guiding and track means and fittings thereon and the means for suspending and holding the auxiliary awning in downwardly extending position.

Fig. 3 is an enlarged partially cross sectional view, with parts broken away of the slideable fittings on a section of the track and illustrating a spring means for releasably holding said fittings in outermost position.

Fig. 4 is a cross sectional view of a fragment of one of the four strips or louvers taken substantially on line 4—4 of Fig. 1, and to illustrate their relatively edge-overlapping position.

As shown on the drawings:

Referring to Figs. 1 and 2, numeral 10 designates a fragmentary section of a window frame and which may vary in a wide range of sizes and shapes. The main or upper awning which is preferably of the ventilated type, comprises a substantially rectangular metal frame formed of four or more metal angle bars. One of the end bars designated as 11 is illustrated in Fig. 2 and has its opposite ends secured by welding or the like to the end portions of the normally longitudinal right angle bars 12 and 13 which latter longitudinal bars 12 and 13 are shown only in cross section in Fig. 2. The longitudinal frame bar 13 adjacent the window frame or building wall is provided with suitable spaced holes in which are mounted a plurality of lag screws or the like, one of which is designated as 14 and is illustrated at the right of Fig. 2. Such fasteners secure the awning frame against the window frame of the building wall in certain cases, and so that the main awning will be in slightly downwardly or upwardly inclined position. The main awning preferably

2

comprises a plurality of adjacent louvers 15 of channel shaped cross section which are secured in interfitting relation and with the angularly bent edge flange 15a of one louver extending in overlapping relation into each of the two adjacent louvers, though the substantially adjacent edge flanges of said louvers 15 being slightly spaced apart to permit movement of air between such spaced apart edge flanges of the respective louvers.

The relative positions of four of said channel-shaped louvers is illustrated in Fig. 4. The respective inclined louvers 15 are secured in the aforesaid overlapping staggered positions by means of a plurality of sheet metal screws 15b which extend through small apertures formed along the opposite ends of said louvers and which thread into suitable spaced apart holes formed in the upper flanges of the outer and inner longitudinal angle bars 12 and 13 which comprise part of the main awning frame.

As illustrated in Fig. 1, the outer ends of the respective louvers 15 are bent downwardly along a longitudinal line substantially coinciding with the outer edge of the outer angle bar 12, and these downwardly bent louver end portions provide a relatively permanent apron and shield 15c which extends a short distance below the outer portion of the frame sufficient to normally shield from the view of persons who are not underneath said awning, the mechanism herein described for retractably mounting the auxiliary sun shield or awning.

Mounted at the opposite two ends of the main awning are a plurality of slightly spaced apart depending panels 17 whose upper edge portions are apertured and are secured to the downwardly inclined frame bars 11 by a plurality of sheet metal screws indicated as 18. The length of the end apron panels 17 may vary within a reasonable degree according to desire.

Referring to Fig. 2, each of the two end angle bars 11 (only one thereof being shown in Fig. 2) has a pair of downwardly extending apertured brackets 20 secured by rivets or the like to the opposite end portions of such frame bar, though a short distance from the ends thereof. Each of said brackets 20 has a lower passaged end or head portion 21 in which are securely mounted the opposite ends of a track or guide bar 22 which is preferably of round cross section. It will be noted that the track bar 22 is securely mounted in a position parallel to the end angle bar 11 and spaced therefrom a short distance.

Passaged fitting 23 is slidably mounted on each of the track bars 22, the same being slipped thereon before the mounting of said track bar with respect to the brackets 20. Each of the slideable fittings 23 has a projecting apertured ear 24 which provides means for pivotally connecting the auxiliary sun shield, apron or awning.

Numerical 25 designates an elongated preferably rectangular, relatively thin sun shield or auxiliary awning which is preferably of metal, though which may be formed of other suitable sheet material. The length of said auxiliary awning 25 is slightly less than the interior longitudinal distance between the two sets of depending panels 17. The upper end edge of the auxiliary shield or panel 25 is suitably connected to a horizontal extending metal rod or pintle 26, for example, by means of a pair of relatively thin metal bands or straps 38 which have their upper ends doubled back and bent to form hinged knuckles therethrough which the pintle or rod 26 extends. The auxiliary awning 25 is secured adjacent its opposite ends to metal anchoring strips or bands 38 by means of spaced apart rivets 39, one of which is shown at the left of Fig. 2, and also by means of the rivets which mount the brackets 33 to said anchoring straps 38 and to auxiliary panel 25. The opposite ends of the rod 26 project beyond the opposite end edges of the auxiliary awning 25 and are journaled in the passages of the ears 24 so that the auxiliary awning 25 is thereby pivotally connected with respect to the two slideable fittings 23.

Each of the fittings 23 has a second apertured ear or eyelet 27 thereon, the latter being preferably formed integral therewith, and said eyelets 27 provide a means for connecting and anchoring one end portion of each of two flexible cables 28 which may be in the form of a rope, chain or the like.

As illustrated at the upper right in Fig. 2, a wheeled pulley 29 is anchored to the window frame by means of

a suitable metal bracket 30 which is secured by screws or the like to the window frame. One of such pulleys 29 is provided for each of the two cables or ropes 28 which thread therethrough in the usual manner.

Referring to Fig. 3, it will be noted that the longitudinal passage through the fitting 23 is of a greater dimension than the circumference of the track 22. The track 22 is provided at a point a short distance from the lower bracket 20 with a recess 31. A leaf spring 32 is mounted within the passage of the fitting 23 and said leaf spring is provided with a projection or abutment 33 which is adapted to seat into the recess 31 when the fitting 23 is moved sufficiently downwardly to cause such interfitting engagement. The said releasable engagement of the abutment 33 with the recess 31 will hold each of the fittings 23 against longitudinal movement on the track rod 22 with respect to normal movements which might be otherwise brought about by wind pressure or the like, though it will be understood that manual pressure or pull imparted to the slideable fittings 23 will overcome the aforesaid engagement and permit the longitudinal movement and elevation of the fittings 23 to the retracted position such as illustrated in dotted lines in Fig. 2.

Mounted on each of the opposite end portions of the auxiliary panel 25 is an apertured bracket 33 which is secured by rivets or the like to the lower portion of said auxiliary awning panel, one thereof being illustrated in Fig. 2. As shown at the lower left of Fig. 2, it will be noted that the auxiliary panel 25 is interposed between the base of the brackets 33 and the respective pivoted metal bands 38 so that the rivets pass through said pivoted bars 38 through said auxiliary panel 25 and through the apertures of said brackets 33 to securely connect the same together. Each of said brackets has an inwardly extending apertured ear to which is connected one apertured end of a brace in connecting rod 34 by means of pins or screws 35, there being one of said braces or connecting rods 34 connected at each end of said auxiliary awning.

As shown at the lower left of Fig. 2, a metal apertured bracket 36 is secured by screws or the like to the window frame 10, and each of said apertured brackets carries apertured ears to which the inner ends of the connecting rods 34 is pivoted by means of suitable pins or rivets 37. Accordingly, the connecting rods or braces 34 are pivoted at each of their ends as described in the foregoing.

It will be understood that the cables or ropes 28 will normally depend downwardly to any convenient accessible position and may optionally be operatively connected to a hand winch if desired. The maximum downward pull on the two separate cables or ropes 28 will retract the slideable fittings 23, first causing disengagement of lug 33 of the spring 32 from the recesses 31 and by such movement, the two said slideable fittings and the auxiliary panel will be moved to the upper retracted position illustrated in dotted lines in Fig. 2, and wherein it is substantially concealed from view with respect to persons who are elsewhere than underneath the awning itself.

When it is desired that the auxiliary awning or sun shield 25 be lowered to partially or fully depending position, the cables or ropes 28 will be released from whatever anchoring means or object to which the same have been tied, and the weight of the braces 34 and of a part of the auxiliary shield or awning 25, will cause said auxiliary awning to move toward the outermost position illustrated in full lines in Fig. 2, and in the extreme outer position, the slideable fittings 23 will have moved to position substantially adjacent the outer brackets 22. It will be understood that the auxiliary awning may be partially raised and retracted to any one of a number of intermediate positions wherein the auxiliary awning will only obstruct the desired amount of sunlight.

Our invention provides an economically manufacturable and quickly mountable adjustable awning which may be used either for commercial display windows or for residence windows.

As many changes could be made in the above construction, and as many apparently widely different embodiments of our invention within the scope of the claims could be constructed without departing from the spirit and scope thereof, it is intended that all matter contained in the accompanying specification shall be interpreted as illustrative and not in a limiting sense.

We claim:

1. In combination with a main awning and a frame therefor, a pair of guide tracks mounted along and below the opposite ends of said main awning frame, a pair of passaged slideable fittings slidably mounted along said tracks respectively; an apertured ear carried by each of said slideable fittings; an auxiliary awning formed of a continuous relatively rigid sheet and pivotally connected at its opposite ends to said slideable fittings respectively; a pair of brackets mounted on the lower portions of said auxiliary awning; a pair of brackets normally mountable on a portion of the building frame below the inner edge portion of the main awning; and a pair of connecting brace rods pivoted at their opposite ends to said brackets on the normally lower edge portion of said auxiliary awning respectively and to the brackets on said wall, said slideable fittings being selectively retractable to move said auxiliary awning into upper retracted position below said main awning.
2. In combination with a main awning and a frame therefor, a pair of track rods mounted along and below the opposite ends of said main awning frame, a pair of passaged fittings slidably mounted along said track rods, each of said fittings having transverse apertures therein; an auxiliary awning formed of a continuous relatively rigid sheet material and pivotally connected along one longitudinal edge thereof to said slideable fittings respectively; a pair of apertured brackets mounted on the lower portions of said auxiliary awning; a second pair of brackets normally mountable on a portion of the building frame below the inner edge portion of the main awning; and a pair of connecting brace rods pivoted at their opposite ends to said brackets on the normally lower edge portion of said auxiliary awning and to the brackets on said wall respectively, said slideable fittings being selectively retractable to move said auxiliary awning into upper retracted position below said main awning.
3. In combination with a normally stationary projecting awning having a supporting frame, a pair of track bars connected to and disposed below the end portions of said stationary awning; a pair of passaged slideable metal fittings slidably mounted on said tracks respectively; depending apertured ears carried by said fittings; a substantially rigid auxiliary panel-like awning pivotally connected to said apertured ears and adapted to pivot into downward and into upwardly extending positions; a pair of metal connecting braces pivoted at their outer ends to the normally lower edge portion of said auxiliary awning; bracket means for pivotally connecting the opposite and normally inner ends of said braces to a window frame or the like; and flexible cable means anchored to said slideable fittings adapted, when pulled inwardly, to move said slideable fittings along said tracks and elevate said auxiliary awning into positions in close proximity to the main awning and into normally concealed position below said main awning.
4. In a two section awning, a main awning frame normally securely mounted at one edge thereof to a building; a plurality of panels mounted on said frame and forming a protecting covering; a plurality of track bars connected to said frame and extending from points adjacent the inner edge of said frame substantially to the outer edge thereof; metal brackets connecting said track bars to said main awning frame; passaged metal fittings suitably mounted on said track bars respectively; apertured extensions carried by said passaged fittings; a plurality of metal bands pivoted at one end thereof to said apertured extensions of said fittings respectively; an elongated relatively rigid sheet-like panels mounted on said bands and extending substantially from one end to the other of said main awning; said auxiliary awning being thereby pivotally mounted with respect to said slideable fittings; a plurality of apertured brackets on the normally lower edge portion of said auxiliary awning; brace rods pivotally connected at one end of each thereof to said last mentioned apertured brackets; means for pivotally connecting the opposite ends of said brace rods to a stationary building portion; and cable means connected to said slideable fittings to provide for selectively moving said slideable fittings inwardly to cause upward and inward movement of said auxiliary awning to positions in close proximity with the under face of said main awning.
5. In combination with a stationary outward projecting awning having a supporting and connecting frame,

a pair of outwardly extending track bars connected substantially parallel to the opposite end portions of said main awning frame; a slideable metal fitting on each of said track bars, each of said fittings having transverse apertures therein; an auxiliary relatively rigid panel having one longitudinal edge portion pivotally connected to said slideable fittings; a pair of brace rods connected at one end of each thereof to the other longitudinal edge portion of said panel and pivotally connectable at their opposite ends to a building portion; cable means connected to said slideable fittings, and pulleys attachable to

a building portion and rollably mounting the intermediate portions of said cables, said cables when pulled inwardly being adapted to move said auxiliary panel upwardly and inwardly to positions in proximity with the main awning.
